UNITED STATES PATENT OFFICE.

LACEY Y. WILLIAMS, OF TOLEDO, OHIO; MARTIN S. DODD ADMINISTRATOR OF SAID
LACEY Y. WILLIAMS, DECEASED.

JOURNAL-BOX AND LUBRICATOR FOR CAR-AXLE JOURNALS.

1,344,667.

Specification of Letters Patent. Patented June 29, 1920.

Application filed January 27, 1917. Serial No. 144,920. Renewed February 10, 1919. Serial No. 276,179.

To all whom it may concern:

Be it known that I, LACEY Y. WILLIAMS, a citizen of the United States, residing at Toledo, in the county of Lucas and State of Ohio, have invented certain new and useful Improvements in Journal-Boxes and Lubricators for Car-Axle Journals, of which the following is a specification.

The object of the invention is the provision of a combined journal box and lubricator, said journal box, interchangeable with the well known type of M. C. B. journal box, having oil receptacles formed therein the walls of which are integral with the box and from which receptacles oil may be delivered by gravity and capillary attraction to the exposed surface of the journal below the bearing, thus insuring constant lubrication under all conditions of service.

20 The imperfections appertaining to common methods of lubrication are so well known to those skilled in the art that they need not be recited.

The invention consists in certain novelties 25 of construction in the box itself and the combination therewith of certain removable parts as hereinafter set forth and claimed.

The accompanying drawings illustrate an example of the embodiment of the invention, 30 the box being constructed and the parts combined therewith according to the best method of procedure I have so far devised for the purpose.

To admit of its interchange with the M. 35 C. B. type of box the general dimensions as to size and exterior shape must conform to the adopted standard so it may receive the pedestal jaws or securing bolts of the truck frame, consequently the receptacles must be 40 formed inside the box and means be provided for filling the oil receptacles and removing and inserting the detachable parts through the box end opening normally closed by the movable cover or lid.

45 Figure 1 is a vertical section in elevation of my improved box lubricator, the journal being in position.

Fig. 2 is a cross section of the complete box on the line 2—2 of Fig. 1.

50 Fig. 3 is a horizontal sectional plan view of the entire box.

Fig. 4 is a perspective view of one oil dis-

tributer detached and the parts separated to show the construction.

Fig. 5 is a sectional view in elevation 55 taken on line 4—4 of Fig. 3, showing the extension of the receptacle under the lug which is engaged by the bearing above the journal.

When formed by casting, the box is preferably integral and has vertical walls A A at 60 each side inside the box and spaced some distance from the vertical exterior sides 1, 1 of the box. B and C are the end walls which form with the walls A A and the sides of the box two oil receptacles each substantially of the same length as the journal 2. These receptacles are closed at the top by the metal of the top of the box and the only openings are those at the bottoms, as D D, for the feeding of the oil to the distributors E 70 E, and at the ends, as F F, for introducing oil into the receptacles.

The oil distributors E E are each preferably of fabric G composed of textile material and spring brass wire, or alternate layers of cotton and woven spring wire, having at one edge a carrier H consisting of a U-shaped strip of metal between the edges of which one edge of the fabric G is securely fastened.

80 The lower edge or flange I of the carrier is wider than the upper edge and adapted to frictionally engage a longitudinal ledge or seat J on the inner vertical surface of the side of the box and located below the opening or openings at the bottom of the oil receptacle.

To hold the carrier in place a flange K is provided which is seated within a recess L formed at the back of the ledge or seat J. 90 The top surface of the carrier engages the lower edge of the end walls bounding the receptacle so it is securely held in position. Obviously, each distributor can be slid endwise into position upon the ledge and also 95 withdrawn by opening the end cover or lid 3 of the box, and after their insertion oil can be introduced to the receptacles by way of the openings F F near the tops of the front end walls bounding the receptacles.

100 It will be observed that the fabric—textile material and the spring wire—bears against the lower edge of a wall A and closes the opening or openings at the bottom of the

receptacle, and that the oil is fed to the side surfaces of the journal by gravity and capillary attraction. The spring textile fabric maintains its position automatically in frictional contact with the journal and the flange 1 of the carrier aids in holding the same in position.

In removing the journal from the box and inserting the same the collar 4 on the journal can temporarily bend the fabric side-
10 wise without injuring it in any way.

Attention in particular is called to the shape of each oil receptacle. In common practice a bearing 5 and a key or wedge 6
15 are located between the journal and the top inner surface of the box, the bearing fitting back of the collar 4 and having a flange 7 back of the rear end of the wedge, which latter at its front end is confined against
20 movement outwardly by lugs 8. To prevent rearward movement of the bearing the inner surface of the box has inwardly projecting lugs 9, 9 which are engaged by lugs
25 upon the bearing at each side, all of which will be readily understood by those skilled in the art. These lugs 9 cannot be omitted, and consequently the spaces forming the oil
30 receptacles, see Fig. 4, extend at each side and below the lugs.

30 In removing and replacing a bearing 5 obviously the distributor need not be removed.

Other parts of the box than those mentioned need not be described, as they are of the well known shapes and locations and
35 dimensions shown by the M. C. B. type of box. However, changes in the box may be introduced which will allow unsubstantial changes in the lubricating elements without rendering the box non-interchangeable with
40 the M. C. B. types of boxes.

In operation the oil feeds by gravity and capillary attraction to the journal, and the flow of oil is determined by the amount which replaces the oil distributed from the
45 fabric to the surface of the journal, for there is no dripping of oil from the fabric to the bottom of the box.

What I claim is:

1. A combined journal box and lubricator having oil receptacles formed inside the box and at the opposite inner sides thereof, each of said receptacles being provided with an opening at the bottom, and a removable oil distributor for each receptacle located and supported so as to engage the metal bounding the opening and close the same and adapted to bear against a journal; said oil distributor being slidably longitudinally of the journal into and out
50 of position.

2. A combined journal box and lubricator having oil receptacles formed inside the box and at the opposite inner sides thereof, each of said receptacles being provided with an
60 opening at the bottom, and a removable oil

distributor for each receptacle slidably longitudinally of the journal into and out of position; each oil receptacle space extending each side of and below the wedge stop lug 9, in substance as set forth.

3. A journal box having oil receptacles inside the box at its opposite inner vertical sides with openings at the bottoms of said receptacles, and a ledge or seat below each receptacle to support an oil distributor
70 which is slidable longitudinally of the journal into and out of position on said ledge or seat.

4. A journal box having oil receptacles formed inside the box, one at the inner surface of each vertical side, the walls bounding the receptacles being cast integral with the box; each of said receptacles having an opening at the bottom, and means below said opening to support a removable oil distributor which is slidable longitudinally of the journal into and out of position when the box lid is open.

5. A journal box having oil receptacles formed inside the box, one at the inner surface of each vertical side, and oil distributors one for each receptacle slidable longitudinally of the journal into and out of position through the end opening of the box; the openings in the walls of the receptacles for introducing oil being inside the box.

6. A journal box having oil receptacles inside the box and at the sides, a ledge or seat for a distributor adjacent the bottom
100 of each receptacle, and a distributor slidably longitudinally of the journal into and out of position on the ledge or seat.

7. A combined journal box and lubricator, the box having oil receptacles formed inside the box one at each vertical side with an opening at the bottom, and removable distributors one for each receptacle and each distributor provided with a fabric of textile and spring wire, said distributors being slidably longitudinally of the journal into and out of position through the box
105 end opening.

8. A journal box having oil receptacles formed inside the box and each receptacle provided with an opening at the bottom, a distributor for each receptacle comprised of textile spring fabric and a carrier, and means for removably supporting the distributor against the metal bounding the
110 opening of a receptacle so the entire flow of oil will be received by the textile and spring fabric and transferred by capillary attraction to a journal; each distributor being slidably longitudinally of the journal into
120 and out of position.

9. The combination of a journal box having oil receptacles at the vertical sides inside the box and each provided with an opening below the bearing surface of the
130

journal, and oil distributers removably supported adjacent the said openings and slide longitudinally of the journal into and out of position, each distributer being 5 provided with a yielding spring fabric adapted to engage the bearing surface of the journal, whereby the fabric may automatically adjust itself in position.

10. A combined journal box and lubricator, the outer surfaces of the side walls of the box lying in substantially vertical parallel planes, oil receptacles located at the sides of the box entirely inside the outer side walls thereof, the inner walls A A of 15 said receptacles being disposed adjacent to the journal and bearing, and oil distributing means inside the box insertible and removable only at the open end of the box.

11. A combined journal box and lubricator, the outer surfaces of the side walls of 20 the box being disposed in substantially vertical parallel planes, oil receptacles located at the sides of the box entirely inside the outer side walls thereof, and yieldable oil distributing means located inside the box 25 and insertible and removable only at the open end of the box.

12. A journal box having oil receptacles at the sides inside the box, and distributing means for oil in connection with the receptacles, said distributing means being insertible and removable only at the open end of the box.

In testimony whereof I affix my signature.

LACEY Y. WILLIAMS.
